US00D973635S

(12) **United States Design Patent** (10) Patent No.: **US D973,635 S**
Park et al. (45) Date of Patent: **** Dec. 27, 2022**

(54) **SOUND BAR**

(71) Applicant: **LG ELECTRONICS INC.**, Seoul (KR)

(72) Inventors: **Seongyeong Park**, Seoul (KR); **Gangho Woo**, Seoul (KR); **Sooyoung Park**, Seoul (KR)

(73) Assignee: **LG ELECTRONICS INC.**, Seoul (KR)

(**) Term: **15 Years**

(21) Appl. No.: **35/512,468**

(22) Filed: **Mar. 3, 2021**

(80) **Hague Agreement Data**

Int. Filing Date: **Mar. 3, 2021**

Int. Reg. No.: **DM/213267**

Int. Reg. Date: **Mar. 3, 2021**

Int. Reg. Pub. Date: **Sep. 3, 2021**

(30) **Foreign Application Priority Data**

Sep. 10, 2020 (KR) 30-2020-0043245
